2,136,262

MEANS FOR MAKING PHOTOGRAPHIC RECORDS OF COUNTING MECHANISM BEFORE AND AFTER USE

Edson S. Hineline, Irondequoit, N. Y., assignor to
 Folmer Grafex Corporation, Rochester, N. Y.,
 a corporation of Delaware

Application July 22, 1936, Serial No. 92,046

45 Claims. (Cl. 235—50)

This application is a continuation as to common subject-matter of my co-pending application Ser. No. 65,260, filed February 24, 1936, and as far as practicable the same parts bear the same reference characters.

This invention relates to improvements in means for making photographic records of a counting mechanism before and after use, together with interlocking mechanism for preventing unauthorized access to such mechanism between the time of making the first and second photographic records, and also for preventing the use of the said mechanism (that is, in this case, voting) before the first photograph has been made and after the commencement of the second photograph.

The invention being especially applicable to voting machines, an embodiment of such a machine is herein shown and described, to which, however, my invention is in no wise limited notwithstanding the ensuing detailed description, excepting where distinctly so stated in claims of the application.

A voting machine, as now constructed, comprises a relatively large board upon which are arranged, in horizontal and vertical rows, a plurality of small card holders, each adapted to contain a card bearing the name of a candidate or of an issue. A plurality of small levers, one for each card holder, are made accessible to the voter, and, by manipulation of selected levers, the voter registers his preference.

In a correspondingly large board at the rear of the machine are arranged in horizontal and vertical rows a plurality of counters, one for each candidate or issue. These counters are so connected to the small levers that each time a lever is manipulated in favor of a candidate or an issue, the register of its respective counter is increased by one in numerical value.

Preferably these counters are turned to "zero" before voting is begun so that an inspection of the individual counters after voting is completed, will accurately inform the inspecting person as to the number of votes cast for each candidate. They need not, however, be all turned to "zero" if a true record (as by a photograph) is made of the counters before and after voting, for in such a case, the numerical value of a counter before voting will be deducted from its value after voting is completed and an accurate count thus achieved.

To operate the voting machine or to vote, it is first necessary to release the machine through a knob or locking means called the "entrance

knob", which allows the curtain to be swung apart for the operator to approach the registering board and again close after the operator has entered. This invention includes means for locking against use of both the entrance knob and the curtain lever before the photograph has been made and also after the commencement of the second photograph.

Part of the mechanism preferably employed in carrying out this invention comprises means for making an accurate photographic record of the counter board both before voting begins and again after it is completed. Mechanism of this character is shown and described in Patent No. 1,977,453, October 16, 1934, to William H. Petit and Edson S. Hineline, and also in the co-pending application of Edson S. Hineline, Ser. No. 65,260, filed February 24, 1936. The present invention, however, comprises a greatly improved mechanical structure for accomplishing this result and provides further interlocking means with respect to the operation of the voting machine and camera mechanism. The present invention also provides improvements in the placement of the various parts that will be described more fully presently.

Another part of the mechanism used in the herein defined structure comprises a magazine adapted to contain and seal the photographic film upon which the record of the counter board is kept, to the end that one not authorized to inspect the record may neither remove it nor otherwise have access thereto. Mechanism of this character is shown and described in Patent No. 1,966,261, July 10, 1934, to William H. Petit and Edson S. Hineline. The mechanism herein shown to accomplish this purpose comprises greatly improved structural details.

The film strip employed in the embodiment of the invention herein shown is substantially that shown in Patent No. 1,963,096, June 19, 1934, to William H. Petit and Edson S. Hineline. This strip embodies such structural variations in its cross sectional contour as will complete an electric circuit at a predetermined position in its travel. The said circuit when completed performs electrically two of the functions of this invention.

By the invention disclosed herein and also disclosed in my said co-pending application Ser. No. 65,260, insofar as the subject matter of the two applications is the same, I accomplish a new result which, so far as I am aware, cannot be attained by the use of any known mechanism and

has not heretofore been practised in any way. My invention involves prevention of access to the counters of a registering or like mechanism from the commencement of the making of the 5 first photographic record thereof, and the registering means are then manipulated (as in a voting or other mechanism) unless and until a second photographic record is made of the condition of the counter board after the manipulation 10 of the registering means is completed. My invention, although herein disclosed as practised upon or in connection with a voting machine, may be employed in many different types of registering or locking means.

15 A new and different object, not heretofore sought to be attained by any known mechanism, is to provide an interlocking means which will prevent all voting or use of the registering or like mechanism before a photograph has been made 20 and after the commencement of a second photograph.

That this new object and other important features are attained will become apparent as the invention is described in detail and reference is 25 had to the drawings wherein,—

Fig. 1 is a rear view of the voting machine with rear doors and counter board cover closed, clearly showing the position of the entrance knob;

Fig. 2 is a fragmentary section taken on the 30 broken line 2—2 of Fig. 1, showing the mechanism for interlocking the upper door;

Fig. 3 is a rear view of a voting machine with the counter board cover open showing the position of the counter board, also the camera and the 35 camera traversing mechanism mounted on the counter board door;

Fig. 4 is a front view of the camera (that is, the side of the camera next to the counter board);

40 Fig. 5 is an end view of the camera taken from the left side thereof when facing the counter board;

Fig. 6 is a partial vertical section through the voting machine showing the relation of the camera and the counter board when the counter board door is in the closed position;

Fig. 7 is an enlarged fragmentary end view of the camera, looking toward the counter board when the camera is in operating position;

50 Fig. 8 is a bottom view of the camera, as when removed from the counter board door;

Fig. 9 is a detail showing in cross-section one of the contacting brushes for conducting electric current to the camera;

55 Fig. 10 is a section through Fig. 11 on the line 10—10 thereof showing a contact mechanism operated by structural variations in the film strip used in making the photographic record;

Fig. 11 is an enlarged horizontal section through 60 Fig. 4 on the line 11—11 thereof;

Fig. 12 is a section through Fig. 11 on the line 12—12 thereof, showing contact mechanism insulatedly supported on the camera for conveying current from the contact mechanism Fig. 10 to 65 the machine proper;

Fig. 13 is a plan view of the film strip showing the structural variations as cut-out portions adapted for the circuit control, said strip comprising the leader strip, the first and second 70 sensitized portions and the trailer strip, the two lines in the center merely indicating a division between that part of the record taken before and that part taken after voting;

Fig. 14 is an enlarged section detail view of a 75 portion of Fig. 11;

Fig. 15 is a view constituting a portion of a bottom view of Fig. 4, showing the arrangement of drive pulleys and gears;

Fig. 16 is a section of Fig. 18 on the line 16—16 thereof;

Fig. 17 is an enlarged vertical section through the lower part of the camera mechanism showing the relation of driving spools, feed roll and exposure openings with respect to the driving mechanism;

Fig. 18 is a shaft spool and gear assembly for driving the take-up spool and also carries overrunning clutch;

Fig. 19 is a horizontal section through the voting machine showing the relation of the drive 15 screw gearing and contact rails with the camera approaching the limit of its left hand traverse;

Fig. 20 is a horizontal section through the voting machine showing the placement of the motor, motor control switching mechanism and 20 the interlocking control for the voting machine entrance knob;

Fig. 21 is a vertical section looking toward the counter board but below the same showing the driving mechanism and control mechanism as 25 placed below the camera mechanism;

Fig. 22 is an enlarged view approximately actual size of one of the counters set at "zero";

Fig. 23 is a similar view with the counter set 30 at 130;

Fig. 24 is a top plan view of the magazine disclosing the method of sealing;

Fig. 25 is a top view of the magazine with the cover removed showing spools in place and the relation of the measuring roll and contact fin- 35 ger;

Fig. 26 is a partial section through Fig. 24 on the line 26—26 thereof;

Fig. 27 is an elevation with parts broken away, showing the magazine cover only, as it appears 40 when it is removed from the magazine proper;

Fig. 28 is a similar view of the magazine with the cover removed, showing the relation of the take-up spool, measuring roll, exposure opening and contact fingers;

Fig. 29 is a vertical section through the voting machine showing the various parts of the interlocking mechanism in its relation to the camera driving mechanism, entrance knob and entrance lever, the machine being shown as locked against 50 voting;

Fig. 30 is an enlarged but similar view of the lower portion of Fig. 29;

Figs. 30A and 30B are details in front and side elevation respectively of the release key and lock- 55 ing bolt controlled thereby.

Fig. 31 is an enlarged sectional view of the voting interlock mechanism in the position that it will be in when the camera has completed its first left hand traverse.

Fig. 32 is a section of Fig. 31 taken on the line 32—32 of that figure;

Fig. 33 is a fragmentary view of the left hand end of the voting machine facing the counter board, showing the relation of the interlock key 85 and entrance knob, certain parts being represented by dotted lines;

Fig. 34 is a sectional view similar to Fig. 31 but showing the voting interlock mechanism in 70 the position that it will be in when the camera has reached the end of its first right hand traverse, thus having completed its first picture, allowing the machine to be voted;

Fig. 35 is a section through Fig. 34 on the line 75

35—35 thereof, showing the position of the index plate;

Fig. 36 is a vertical sectional view similar to Fig. 29 excepting that the parts are shown in Fig. 36 as positioned to permit voting;

Fig. 37 is a sectional enlarged detail of Fig. 36 disclosing the operation of one of the interlocking switches;

Fig. 38 is an enlarged detail of a portion of Fig. 36 showing the door interlock mechanism;

Fig. 39 is an enlarged vertical sectional view corresponding to the lower portion of Fig. 36;

Fig. 40 is a detail view showing the switch key control for starting the camera traverse mechanism;

Fig. 41 is an end view of Fig. 40;

Fig. 42 is a view similar to Fig. 40 excepting that the switch is in a different position;

Fig. 43 is a view similar to Fig. 40 but with the switch in still a different position;

Fig. 44 is an end view of Fig. 43;

Fig. 45 is a partial vertical section of the voting machine showing the placement of various parts of the interlock mechanism;

Fig. 46 is a similar view but with the interlock parts occupying a different position;

Fig. 47 is a view in front elevation facing and below the counter board, showing the knob for setting the index of the interlock mechanism;

Fig. 48 is an end view partly in section of Fig. 47;

Fig. 49 is a diagram of the electrical circuit when the counter board door is open;

Fig. 50 is a portion of the circuit diagram showing the position of the film strip under the electrical contacts when the magazine is placed in the camera;

Fig. 51 is a portion of the circuit diagram showing the position of the contacts in relation to the film strip when it has been wound to a signalling position;

Fig. 52 is a similar view showing the position of the contacts in relation to the film strip when it has been wound to its starting position;

Fig. 53 is a circuit diagram with the magazine in place, the upper door and counter board cover closed and the switch which is operated by the camera key in contact and the motor running in the forward direction to drive the camera across the back of the voting machine;

Fig. 54 is a circuit diagram at the time the camera reaches the extreme left hand point of travel in which position the motor is caused to reverse whereupon it will travel in picture making direction, said diagram showing the illumination switch closed; the voting machine door in closed position and the interlock latch tripped by the camera mechanism; and

Fig. 55 is a circuit diagram illustrating the condition after the camera has returned to the full right hand position, the door still being closed, the paper positioning contacts as shown in Fig. 51 causing a solenoid to be energized to withdraw an interlocking pawl, the motor switch and the light switch both being open while the door is still closed.

Fig. 56 is a front view of the voting machine with the curtains open for the entrance of the voter;

Fig. 57 is a partial view of the back of the voting machine showing the interlock mechanism as used on the so-called Jamestown machine, manufactured at Jamestown, New York;

Fig. 58 is a chart showing the various switches

in their respective positions at certain parts of a complete cycle of operations;

Fig. 59 is a partial detail of Fig. 42 of the patent to Moore No. 1,172,548, dated February 22, 1916, showing how the herein disclosed interlocking mechanism is applied to said patent, which is selected merely as a convenient example of voting mechanism;

Fig. 60 is a plan view of the interlock disk attached to shaft H of said patent showing said disk in an unlocked condition; and

Fig. 61 is an enlarged detail of Fig. 59 showing the mechanism in an unlocked condition.

The mechanism comprising this invention is positioned entirely on the rear or counter board side of the voting machine, but a view of the front or voters' side of the machine is provided in Fig. 56. In the rear elevation Fig. 1, the machine proper, broadly designated by the numeral 50, has an upper door 52, a counter board 15 cover 54, a middle door 56 and a lower door 58, all for closing the operative mechanism. The middle and lower doors 56 and 58, have no function in connection with the counting mechanism herein defined.

The locking mechanism of the upper door 52 comprises a knob 60, the turning of which operates a bolt 62 (see Fig. 2) from the dotted position 64 to the position 66 therein, in which full line position the end 74 of the bolt enters behind the edge 70 of the housing to retain the door in closed position. The upper door key 72 may be turned in one or the other direction to secure the knob 60 against turning or to release it for unbolting as desired.

Projecting laterally from the bolt 62 is the interlocking end 74 in front of which a vertically operative locking bar 76 (shown in elevation in Figs. 29 and 36) may be made to extend to prevent unbolting of the upper door. This locking bar 76 is operable vertically into and out of its position in front of the projection 74 by the voting release key 78, through the locking bolt 76^a that is attached to bar 76, thus serving, with means subsequently to be described, 45 as an interlock whereby the upper door 52 may not be unbolted after the voting machine is thus made available to the voter. The said bolt 76^a in its relation to the release key 78 is shown in Figs. 30A and 30B, and is also indicated in 50 Figs. 29, 36, 45 and 46. Viewing said figures, it will be seen that what may be a common type of drawer lock 76^b is secured to a side wall of the casting. The bolt 76^a of that lock is secured by a screw or rivet 76^c to the locking bar 76. 55 The bar 76 also carries an L shaped member 81 (shown most clearly in Figs. 37 and 38). When the bar 76 is caused to move upward as just explained, it carries the L shaped member 81 with it, which then engages a stud 75 permanently fastened to door 54, thus also locking door 54.

The counter board cover 54 is hinged at the lower edge at 80 (see Figs. 6 and 29) and its upper edge has a lip 82 (see Fig. 3) which extends upward and is covered by the upper door 52 when the upper door is closed.

It will be clear that when the counter board cover 54 is closed and the upper door 52 is closed over its upper edge and bolted as shown in Fig. 1, and the voting machine release key 78 is turned to make the voting mechanism available to the voter and to interlock the upper door bolt, so that it may not be turned to open position, the camera 84 and the counter board 75

86 may not be tampered with, after initial movement. To make it necessary to close the door 54, the stud 75 on door 54 extends through an opening in the voting machine frame 83 (as shown most clearly in Figs. 37 and 38) and contacts an electrical switch through member 434 operating switch 432 (hereinafter more fully referred to), which completes the circuit as shown in Fig. 53. The camera cannot be operated until this door is closed. This particular part of the interlocking mechanism will be described more fully later in the specification. It will be understood that the casing having a cover such as the counterboard cover 54 or the upper door cover 52, or both, constitutes a barrier to prevent access to the registering means of the voting mechanism which is indicated generally in Fig. 56.

Inasmuch as the mechanism of this invention includes means whereby two photographic records of the counter board are made and the total count for any candidate or issue is the difference between the numerical value of the corresponding counter as recorded on the first and second photographs, it becomes important that means be provided to prevent turning of the voting release key between the time that the camera begins to take the first photograph and the time at which it has completed the last, and also to prevent voting or operation of the machine prior to the time of making the first photograph or after the commencement of the making of the second photograph.

The combination of mechanically and electrically operated mechanism provided to attain this result will be hereinafter described.

In Fig. 3 is shown camera 84 mounted on the counter board door 54 there shown open, and displaying the counter board 86. The traversing mechanism is in many respects similar to that shown in said Petit & Hineline Patent No. 1,977,453. The camera 84 itself, more clearly shown in Figs. 4, 5, 6, 7, 8, 11, comprises a vertical row of lenses 88, spaced and positioned to correspond to the horizontal rows of counters 90, on the counter board, whereby each lens may traverse and progressively be focused upon an entire horizontal row of counters. In the operation of the mechanism, the camera is traversed in a picture-taking direction twice past the counters, once when the counters have all been turned to zero position, as shown at 92 in the enlarged view Fig. 22 and again after voting is completed, when the counters show a register of their respective counts, as at 94, in the other enlarged view Fig. 23.

A carriage 198 (Fig. 4) on the base of the camera carries a pair of rollers 98 (Fig. 5) which support and guide the camera on its transverse movement by rolling on the track 200 (Fig. 6). The camera is moved and controlled by a coarse pitch screw 102, which may be called the camera traversing screw, and a bar 104 which may be called the camera control bar or rod. The manner in which this screw and bar control the transverse movements of the camera will hereinafter appear. A series of light bulbs 106 are arranged to light the counter board as they traverse it, and a corresponding series of angle mirrors 108 transfer the image of the counters being traversed through a series of lenses 88, light tunnels 110 and exposure openings 111 (see Figs. 11 and 26) to the film strip 112 within the magazine 114.

The magazine 114 contains the film strip 112 shown in detail in Fig. 13, which, before exposure, is wound on the film strip supply spool 116, and,

during exposure, is transferred from the film strip supply spool 116 to the film strip take-up spool 118. A feed roll 120 is rotated during movement of the camera at such a speed as will move the film strip past the exposure openings 111, at the same rate of speed as the camera is traveling. Driving points 122 (shown enlarged in Fig. 14) penetrate and engage the strip to insure that the movement of the strip will be the same as the peripheral speed of the roll. A small guide roll 10 124 is positioned to maintain engagement of the strip with the driving points.

An insulating block 126 (see fragmentary section Fig. 10) secured to the frame of the magazine 114 contains the contact members 128 and 130, which are urged by the springs 132 toward the film strip 112, whereby the ends of the contact members are normally held against the surface of the strip. A metal bridge 134 electrically connects the contact member 128 to the contact 20 member 130.

Insulatedly supported on the cover 136 of the magazine by the strip 138 (shown most clearly in Fig. 12) are two electrically conductive strips 140 and 142 adapted to convey current from the contact members 128 and 130 respectively to the rear of the magazine cover. The rear ends of the strips 140 and 142 overlie openings 144 in the magazine cover 136, whereby spots on the strips are accessible for electrical connection from the 30 exterior of the magazine when it is closed.

An insulating member 146 is secured to the camera frame 148 by the screws 150. Member 146 (Figs. 11 and 12) carries the contact members 152 and 154 adapted to extend through the openings 144 and make contact with the strips 140 and 142 respectively. By means of the flexible flat conductive blades 156 the contact members are resiliently held in electrical contact with the strips. Protective insulating layers 158 and 138 40 (see Figs. 10 and 12) overlie the conductive strips 140 and 142 where they are proximate other metal parts within the magazine. Insulating strip 158, however, has openings 162 through which the contact members 128 and 130 may extend and electrically connect the strips 140 and 142 through the bridge 134, when the film strip 112 does not overlie the openings 162. It is apparent that properly positioned openings, such as 164, 166, 168 and 170 (Fig. 13) in the film strip will permit the contact members 128 and 130 electrically to connect the strip 140 to the strip 142, whereby electrical current may flow in through one strip and out through the other.

Below the camera 84 near and parallel to the track 200 are three electrically conductive rails 172, 174 and 176 (shown mostly clearly in Figs. 19, 49 and 53), all secured to insulating blocks 178 by rivets 180. The blocks 178 are held to the machine proper by screws 182. The contact member 152 (Fig. 12) is electrically connected to the rail 172 through a wire 184 (Fig. 11) which is secured to a flexible sliding brush 186, carried on an insulating block 188 (Figs. 8 and 9) on the bottom of the camera. The contact member 154 is electrically connected to the rail 174 through a wire 190 (Fig. 53) which is secured to a flexible sliding brush 192 (Fig. 8) also carried on the insulating block 188.

A third flexible sliding brush 194 (Figs. 7 and 70 8) carried by the insulating block 188 makes electrical contact with the rail 176. A wire 188a connects the brush 194 to the brush 186 through the bank of lamps 106 (Figs. 49 and 53) which are connected in series.

As shown most clearly in Figs. 6 and 7, on the lower surface of the camera 84 is formed a housing or carriage 198 within which the film strip feeding mechanism is contained. The camera traversing screw 102 and the camera control bar 104 extend longitudinally through this housing. Adjacent and parallel to the camera traversing screw the camera guide rail 200 extends across the machine. Guide rollers 202 rotatably carried on the top of the camera bear against the front and rear of the guide rail 222 (Fig. 6) to prevent the camera moving toward or away from the counter board during its transverse movement.

15 A block 204 internally threaded to fit over the screw 102 is secured to the bottom of the camera 84 by the screws 206 (Fig. 8), whereby rotation of the screw backward or forward moves the camera in one or the other direction across the 20 counter board.

In order to compel movement of the film strip 112 across the exposure openings 111, at a speed corresponding substantially to the speed with which the camera traverses the counter board 86, 25 the feed roll 120 (Figs. 11 and 17) is positively driven by a rack and gear movement. The rack 208 (Fig. 6) is carried on the rail 200. A gear 210 having a pitch diameter equal to the outer diameter of the feed roll 120 is rotatably supported at the top in casting 199 and at the bottom in a bearing 212 (Figs. 17 and 18).

It is desirable for reasons hereinafter explained that the feed roll 120 be rotated only when the camera is traversing the counter board 35 in the one direction, but will remain non-rotative when the camera is traversing the counter board in the other direction. To effect this end, the rack gear 210 contains within its relatively large bore a unidirectional clutch 215. This 40 clutch is shown in horizontal section in Fig. 16 and is of conventional roller clutch design having rollers 217 and springs 219.

A second gear 216 (Fig. 17) is axially spaced from the clutch 215 by a projection thereon. 45 Also part 215 is integral with gear 216 and fitted in the bore of 216 is a bushing 226. The gear 210 and gear 216 together with rollers 217 and springs 219 constitute a conventional over-running clutch. This clutch is free to revolve on shaft 230 between collar 228 and driving sheave 256. Keyed on shaft 230 with a pin 234 is a driving sheave 256. Said driving sheave is driven by spring belts 240 and in turn drives take-up spool 118 through driving tang 236 and splined socket 237. Said feed roller 120 is driven by gear 210 being turned through contact with rack 208 as the camera travels in the forward direction. This motion is then transmitted through over-running clutch to gear 216, then to gear 254 and gear 248 which is pinned to feed roller driving spindle 231, which drives this roller through tang shaft 236 and splined socket 237.

Also on said shaft 231 is pinned a large driving sheave 252 which drives the spring belts to take-up sheave 256 previously referred to. Take-up spool 118 is frictionally driven at a higher rate of speed than feed roller 120. This will tend to keep a tension on the film strip as it passes over film exposure opening 111. Spring belts 240 are free to slide over sheaves 256 and 252 when the load on sheave 256 reaches a point which is just sufficient to keep film strip 112 taut across the exposure opening 111.

The magazine proper, which is generally designated by the numeral 114, is shown in Figs. 11

and 24 to 28 inclusive, and comprises a vertical plate 260 having a top head 262 and a bottom head 264 extending laterally therefrom. A double walled partition 266 extends at right angles from the vertical plate and is divided by small 5 plates 268, whereby there are provided the light tunnels 110 corresponding in number to the number of lenses 88 in the camera 84.

The feed roll 120 and idler roll 258 are rotatably supported in bearings in the top and bottom heads 262 and 264. The supply spool 116 and the take-up spool 118 have rotative bearing in the bottom head 264, but in the top head their journals 239 are supported in U shaped slots 267, whereby the spools 116 and 118 may have their 15 axes inclined outwardly to permit the spools to be entered or removed from the magazine.

The film strip 112 comprises a leader strip 270, a first sensitized portion 272, a second sensitized portion 274 and a trailer strip 276. The film strip 20 is put on the spools by inserting the ends 278 and 280 in slits 282 in the take-up spool 118 and supply spool 116 and turning the spools until the strip is taut.

The magazine cover 136 (Fig. 11) fits over and 25 closes the magazine after the film strip 112 has been put on the spools 116 and 118, and the spools put in their bearings. When the magazine, the film strip and the cover are thus assembled, the openings 164 and 166 as well as 30 the openings 168 and 170 in the film strip are in alignment with the contact members 128 and 130 or may be brought thereunder by movement of the strip from one spool to the other. A stud 284 (Figs. 24 to 26) extends upwardly from 35 the magazine top 262 through a small hub 286 on the cover 136. A cross hole 288 extends through both stud 284 and hub 286, and a wire 290 extends through the cross hole and is held clamped in a lead seal 292, whereby the cover 40 136 may not be removed without breaking the seal 292.

As shown most clearly in Fig. 3, the coarse pitch screw 102 which causes transverse movement of the camera 84 is rotatably mounted at 45 the left end of the machine in a bearing 294 secured to a bearing plate 296. The bearing plate is secured to the machine frame by screws 300. A like bearing is also provided on the right hand end of lead screw 102. Attached to lead screw 102 is a small pinion gear 298 (shown also in Fig. 30). Meshing with pinion 298 is a gear 232 carried in a cradle-type bearing 306, which is mounted upon the body of the voting machine. Said bearing cradle is pivoted on shaft 244a (Fig. 50 21) on the body of the voting machine and caused to move upward with spring 293 (Fig. 30). The gear 232 meshes with a pinion 234 (Fig. 19) carried on shaft 256. A bevel pinion 242 is also carried on shaft 256. Said bevel pinion also 55 meshes with a bevel pinion 240 carried on a vertical shaft 250 (Fig. 30). Bevel gear 240 is keyed to shaft 256 with pin 244 and is in turn coupled to motor gear reduction housing 314 (Fig. 19) through coupling 308, more clearly 60 shown in Fig. 21. At the lower end of coupling 308 in gear housing 314 (as shown most clearly in Fig. 20) a worm gear 318 is attached to coupling shaft 310 (shown also in Fig. 39). Meshing with gear 318 is a worm 324 mounted on motor shaft 320. The purpose of mounting gear 232 in a swivel or cradle-type bearing 306 is to 65 allow the door 54 carrying screw 102 and gear 298 to be opened and closed irrespective of the position of these gears. For instance, if the 70 75

door should be closed and the gears did not mesh, bearing plate 306 would be forced downward and when the motor started to rotate, gear 232 would turn until gears do mesh and spring 293 would cause bearing plate 306 carrying gear 232 in position properly to mesh gear 232 with gear 298. The mounting of the camera for traversing movement upon the inside of the door 54 involves a very extensive reorganization of parts over the construction shown in the patent to Petit and Hineline No. 1,977,453, wherein no barrier or door is provided, the camera or photographic apparatus in that patent being mounted with all its parts for traversing movement on tracks fixed on the body of the voting machine. By mounting the camera upon the inside of the door 54 a number of important results are accomplished. Not only is the camera entirely concealed from observation or tampering upon the inside of the barrier, by the act of shutting the door 54, but it is readily possible to manufacture or assemble the door 54 and the camera with all its parts as a single unit at the camera factory, leaving the voting machine proper to be manufactured at a wholly different factory that may be in a distant city. This permits the camera to be adjusted and mounted upon its own door, and the cameras may thus be all readily tested each with respect to a single voting machine body before being shipped to the voting machine factory. This simplifies the procedure of manufacture to a considerable extent, and therefore lessens the cost of manufacture. By having a yielding interengagement of the parts that are respectively upon the door and the voting machine body, it is possible to accomplish all the foregoing and yet secure proper operation of all the mechanism.

Camera 84 must be caused to travel both to the left across the counter board and again to the right. This is accomplished by reversing the electric motor (that is, reversing the direction of rotation of electric motor 322, Fig. 39). Said motor 322 (Figs. 39 and 20) is caused to operate by having on its field two separate and distinct field windings wound so as to cause opposite directional flow of the electromagnetic forces. Thus when the current flows through one field, the motor will operate in one direction, and when it flows through the other field, it will operate in the opposite direction. This will be discussed further with respect to the circuit diagram, Figs. 49-55. By this construction I can use a simple double throw single pole switch which simplifies the construction materially. For instance, a single switch (that is, a double throw, double pole switch) can be used for controlling both the motor and the lights 106. One half of this switch is used as a single pole, double throw switch, and the other half is used as a single pole, single throw switch. These switches are designated as switch 338 and 340 in Figs. 20 and 21. The portion 338 of the switch to be used for the reversing of the motor is shown in the circuit diagram Figs. 49, 53, 54 and 55. It will be seen that if the motor runs in one direction, the camera will travel across the counter board in one direction, either from left to right or right to left, depending wholly upon the position of switch 340.

As clearly shown in Fig. 20, switch 338 and 340 is mounted on gear housing 314 with a cross plate 334. One portion of this switch is used for reversing the motor as has been explained and the other portion is used for controlling the series

bank of lamps 106. Supported in the end plate 332 is a conventional cylinder lock 364, to the inner end of the barrel of which is secured a switch operating cam 366 (Figs. 40-44). The turning of key 368 therefore operates the cam in a limited rotative movement. A stud 370 extends laterally from cam 366, and a similar stud 372 (Fig. 20) extends laterally from gear housing 314. A spring 374 tensioned by having one end secured to stud 370 and the other end to stud 372 urges the cam rotatively in a direction which is counterclockwise when viewed from the front. On the face of cam 366 adjacent to the plate 332 are the latch lugs 376 and 378, Figs. 40 and 41. Flexible latch members 380 and 382 are secured to the inside of the plate 332 by the screws 384. Members 380 and 382 carry latch lugs 386 and 388 respectively, which are adapted respectively to engage the lugs 376 and 378 at different periods in the operation of the camera 84. A notch 390 in the periphery of the cam 366 receives the tumbler 392 of the switch 344, whereby rotation of the cam 366 to different positions operates the switch to its "on" and "off" positions.

The upper ends of the latch members 380 and 382 are extended laterally and downwardly (Figs. 41 and 44), the downwardly extending ends 394 and 396 being adapted to be engaged by the two adjustable screws 398 and 400 (Fig. 34), held in lugs 402 which extend upwardly from the lever 348, whereby movement of the lever by the bar 104 in one or the other direction caused by the movement of the camera in one direction or another also flexes the latch members 380 and 382, thereby operating their lugs 386 and 388 (Fig. 41) with respect to the cam latch lugs 376 and 378.

As shown in Fig. 19, lever 356 has a boss attached at 363 which in turn is pinned onto vertical shaft 346 shown in an enlarged view Fig. 21. Said vertical shaft 346 has a bearing in plate 100 and in gear housing 314. Attached to bed plate 100 (Fig. 19) is the reversing bar 104 previously referred to as the camera control bar or rod, which is held to bed plate 100 with screw 312 and washer 314. A similar screw and washer is applied to the other end of the bar. This bar has slots 407 allowing it to be shifted both to the left and to the right. On the bar 104 is attached a block 352 in which a pin 350 is fastened through a slot in lever 356 shown in Fig. 19 at 354. Pin 350 which engages in slot 354 of lever 356 causes lever 356 to be moved in a clockwise or counterclockwise direction depending upon the direction of movement of bar 104. Said lever 356 has attached thereto an upper collar 363 which in turn is pinned to shaft 346, and as lever 348 is also attached to vertical shaft 346 any motion of lever 356 will also cause a like motion of lever 348. Attached to said bar 104 (Figs. 11 and 19) is an L shaped plate 362, held to bar 104 with screw 316.

Best shown in Fig. 19 and also in Fig. 8 is lever 326 mounted at the side of the camera 84. This lever is provided with a screw 328 which goes through an elongated slot in lever 326, and is held in the forward position by springs 405, one end of which is attached to a pin 365 in said lever. The other end of said spring is attached to a pin 336 in the casting of camera 84. Said lever 326 is held against the side of the camera casting by a spring 330 and a screw 332. This spring serves to allow lever 326 to give somewhat laterally when the camera reaches the end of its travel and contacts with bent up stop plate 362. The function of this lever is as follows:

When camera 84 travels to the left and just

before it reaches the limit of its left hand travel, lever 326 contacts with bent up plate 362 and causes bar 104 to be carried along with it. Thus through the various actions of levers just described, the motor is reversed. This also reverses the direction of camera travel. When the camera reaches its full right hand movement, it contacts with the other bent up member 362 and causes bar 104 to travel with it to the right, thus again causing a movement in the parts to shift switch 338 and 340 to a reverse position. The lock 364 is also caused to be turned off, thus stopping the camera motor and the camera travel. A more full description of the switching mechanism in its operation will be given at a later point in the specification.

A lamp 401 (diagrams 49, 53-55) is connected in series with the bank of lamps 106. This lamp when lit is visible through an opening 399, Fig. 1. This gives an indication, when the switch board is closed and a photographic record is being made, that the bank of lamps 106 is lit.

When key 78 at the left of the machine is turned (Figs. 1 and 3) the interlocking bar 76 (which is attached to a suitable bolt of the lock) (Figs. 29 and 36) is thereby raised to interlock with the upper door bolt 62, and with the central door 54 through stud 75 which has a notch 79 (Figs. 37 and 38). Bar 76 has a piece attached to it so shaped as to fit in slot 79 and prevent door 54 being opened. This prevents access to the counter board as hereinbefore explained. The locking bar 76 draws upwardly with it an interlocking bar 404. The lower end has a latch lug 406, Fig. 36. Figs. 29 and 30 both show interlock bar 404 in the raised position. A latch bar 408 is pivotally supported on the machine at 410, and is joined by a link 412 (Figs. 45 and 46) to an electromagnetic element 414. A tension spring 416 normally draws the latch bar 408 toward the left. The latch bar 408 extends horizontally as indicated at 418 for a short distance, then again vertically, as shown in Fig. 36. At the extreme upper end of bar 408, pin 420 extends laterally. A release latch 422 (Figs. 45 and 46) is hinged at the frame at 424. A hook 426 on latch 422 is drawn downward by spring (not shown) over pin 420 when the locking bar 408 is in the position shown in Fig. 45. The hook 426 may, however, be raised away from the pin 420 by downward pressure on the trip end 430, and thereby the locking bar will be drawn by the spring 416 from the position shown in Fig. 45 to the position shown in Fig. 46. The interlock bar 404 has previously been raised to the position shown in Fig. 45 by turning the voting release key 78 (Fig. 1), thereby locking both the upper and the central doors on the back of the voting machine.

In operation the cam block 431 secured to the bottom of the camera 84 is caused by the camera traverse movement to pass over and depress trip end 430. The cam is long enough to hold the bar 422 in unlocked position for the initial movement of the film. As long as the locking bar 408 remains in the position shown in Fig. 46, its horizontal exposed portion 418 fits under the latch lug 406 whereby key 78 may not now be turned and therefore the locking bar 76 may not be withdrawn from this opening of the doors which give access to the counter board. When it becomes desirable again to return the latch bar 408 to the position shown in Fig. 45, it is done electrically (that is, by energizing the electromagnetic element 414), which is done by completing an electrical circuit to contact members 128 and

130, when the holes 168 and 170 allow said contact members to extend therethrough. A signal lamp 415 (diagram Figs. 49, 53-55) is connected with electro-magnetic element 414. Lamp 415 is visible through an opening 417 in the machine frame (Figs. 1 and 3) and thereby indicates when the contacts 128 and 130 have extended through the openings in the film strip 112.

An added precaution against tampering and as a means to prevent human contact with any of the electrical elements, there are provided three conventional switches 432 operable to break the circuits by the movement of the upper door 52 and the contour cover 54 in opening the same. Two are shown in Figs. 29 and 36. A pin 434 is pressed by the covers 52 and 54 against the resistance of a spring (not shown) to close the circuit when the door is closed. Fig. 36 shows the doors closed and the switches 432 in the closed position. Fig. 37 is an enlarged view showing that the pin 75 has a projection to close switch 432 added to its extending arm 434. In Fig. 29 the doors are shown open and the switches in the open position. In Fig. 36 the bar 76 is shown as connected to bar 404 with a connecting link 428 positioned by a short lever 438. Attached to bar 428 is a formed metal piece 440 with lips drawn up on its outer end to cause the switch 433 to function as bar 76 is caused to move upward or downward. Switch 435 prevents the motor from being run when entrance knob 218 (Figs. 29 and 36) is raised. The switch 433 is caused to function when entrance key 78 is turned to lock the voting machine through connecting bar 428 and projection 440. In Fig. 35, there is shown a chart which indicates the various switches herein referred to, in their respective positions at certain parts of a complete cycle of operations.

The voting machine is equipped with a lever 40 which is commonly called a curtain lever which when swung to the left closes the curtains around the voter and allows the machine to be unlocked for voting if the entrance knob is released by the voting official. It is very desirable to lock the machine against voting excepting at the proper time, that is, the machine should not be allowed to be voted before a photograph has been made nor after a second photograph has been made. In other words, the only time the machine can be voted is the period between the completion of the first photograph and the start of the last photograph. The mechanism for carrying out this part of the invention will now be described. The entrance knob 218 has already been referred to. I will now describe the means for locking it.

In Figs. 29, 36, 56 and 57, the voting machine curtain lever is shown at 445 and the curtains at 445a. This lever is mounted on the top of the voting machine. Attached to lever 445 by means of a short shaft is disk 446 having a hole 448. Whereas in Figs. 29 and 36 merely a short shaft is shown having fast thereon said disk 446, I have in Figs. 59, 60 and 61 represented the same disk 446 as fast on a shaft H of the said Moore Patent No. 1,172,548, in order merely to make it clear how the mechanism of my invention may be applied to voting mechanism, said patent to Moore being selected merely as a convenient example of voting mechanism, and not being selected for purposes of limitation. In Fig. 29, a pin 447 is shown as positioned within the hole 448 of disk 446. Attached to the top plate of the voting machine is a small bracket 453 to support rocker arm 449 pivoted thereto at 75

451. This rocker arm carries the pin or stud 447 to engage the hole 448 in plate 446. The rocker arm 449 is controlled by voting entrance knob 218 previously referred to, through a connecting rod 450 pivoted to the rocker arm 451 at 452. Also positioned on the connecting link 450 is a forked metal piece 454 attached to a plate 455 for operating switch 435. I have not herein shown a complete voting machine, since my invention may be suitably applied to various types of voting machines, and therefore is not limited in its application to any particular type of voting machine. For example, it may be and is desirably applied to the so-called Jamestown voting machine previously referred to. However, for readiness of explanation (but without in any way limiting my invention), I have in certain figures of the drawings, as already set forth, represented it as applied to voting machine mechanism shown 20 in the expired patent to C. C. Moore, Jr., No. 1,172,598, dated February 22, 1916, wherein at H in Fig. 42 thereof is shown a shaft corresponding generally to the short shaft shown in Fig. 36 hereof as having curtain lever 445 secured thereto, and which shaft H of the said Moore patent may readily receive or have applied thereto mechanism shown in Fig. 36 of the drawings of this application, wherein appears curtain lever 445, and which curtain lever corresponds generally to the bar C of Fig. 2 of the said Moore patent. Such connections I have represented in Figs. 59, 60 and 61, and which need not be again described.

A second rocker arm is connected to the bar 450, clearly shown in Fig. 29 at 460. This rocker arm is pivoted at 461 and has attached to it on one end a bar 463 pivoted at 462 and extending downward through a bracket, best shown in Fig. 39 at 469. Said bracket 469 is riveted to the 40 left end wall of the voting machine casing, clearly shown in Figs. 21 and 31. Bracket 469 has a stud 480 riveted to the bracket and carried on stud 480 is a cylindrical member 470. A section of the member 470 is very clearly shown in 45 Figs. 32 and 35. On either end are short, equally spaced pins shown on the right end of 470 at 466 and on the left end of 470 at 471. A ring 464 is also carried on the member 470 having four equally spaced notches 465, as shown in Fig. 32. Also attached to member 470 is a dial 474 having a knob 475 used for resetting indexing mechanism.

The cylinder 470 is caused to rotate in one direction by means of pins 466, 471, ratchet pawls 55 472, 468 and rocker arm 467, attached to shaft 346. Any movement of said shaft imparted to it by bar 104 with resulting movement of rocker arm 467 and pins 466, 471 causes cylinder 470 to advance around stud 480 in a counterclockwise direction as viewed in Fig. 32. Each cycle of camera movement causes bar 104 to transmit to rocker arm 467 one motion; that is, when the camera travels all the way to the left, it causes shaft 346 to be turned in a clockwise direction 60 carrying rocker arm 467 and pawl 468 and one of the studs of cylinder 470 to a position shown in Fig. 31, the end view being as in Fig. 32. A dowel 463 has a reduced portion 476 which is of a size that will drop into a notch 465 in ring 464, if a notch 465 is under dowel point 476. At 65 the completion of the first cycle or the first travel toward the left of the camera 84, index ring 464 and dowel 463 will be positioned as shown in Fig. 32. As the camera travels to the right, shaft 346 is caused to turn in a counterclockwise 70 75

direction by the movement of bar 104. The index cylinder will then be positioned as shown in Fig. 34 and end view Fig. 35. The dowel point 476 can now enter one of the notches 465 in index ring 464, as clearly shown in Fig. 35. This 5 is at the end of the second cycle or after the first picture has been made.

When index ring 464 was positioned as in Figs. 31 and 32, the dowel 463 connected to entrance knob 218, as described previously, could 10 not have been moved downward to cause pin 447 (Fig. 29) to be withdrawn from hole 448 in disk 446, thus allowing curtain lever 445 to be operated. But as the mechanism is now positioned as shown in Figs. 34 and 35, a notch 465 in index 15 plate 464 is positioned to allow dowel point 476 on bar 463 to enter notch 465 in index plate 464, thus allowing entrance knob 218 to be moved from its position with relation to its associated parts, as shown in Fig. 29, to the position as shown 20 in Figs. 36 and 61. This condition of parts is maintained until a further cycle of the camera takes place, namely, the operation of moving camera to the left of the board, prior to taking the second picture. So long as the mechanism 25 can be arranged as shown in Figs. 36 and 61, the machine can be voted. When the camera completes its second left hand travel, index plate 464 on cylinder 470 will be caused to turn the space of one notch to a position where dowel 30 pin 475 and dowel 463 can no longer drop into one of the notches 465. Therefore, no further voting can take place. The next cycle of the camera (that is, of taking the second picture of the series) will cause index plate 464 carrying 35 notches 465 to be further turned in a clockwise direction, but this still does not allow dowel point 476 of dowel 463 to enter one of the notches 465. The position of index plate 464 will be as shown 40 in Fig. 39, and no further voting can take place until the mechanism has been reset by setting dial 474 with knob 475 clearly shown in Fig. 48. It will be noted that this index mechanism can be set in any one of four positions, and be in correct placement for the commencement of the 45 operation of the various cycles of the voting machine camera. When entrance knob 218 was moved upward, it carried with it formed metal part 454 which operates switch 435 to break the circuit of the motor switch. The function 50 of this switch is clearly indicated in circuit diagram Fig. 49.

The circuit diagrams Figs. 49 to 55 are given numerals to correspond in so far as possible to the operative elements of the structure and are 55 used as is also the chart of Fig. 58, in describing the operation of the mechanism which is as follows:

Magazine cover 136, Fig. 27, is removed from magazine 114, Fig. 3. A specially prepared day-light loading cartridge is placed in position on the spool 116, Figs. 11 and 28. The leader strip is drawn out under guide roller 124 (Fig. 11) over feed roll 120, over exposure opening 111, over idler 258, and started onto the take-up 60 spool 118, which is turned only sufficiently to allow the leader strip to be firmly engaged on the spool 118. Cover 136 (Fig. 27) is then placed on the magazine 114 (Fig. 28) and a seal 282 is then placed in the voting machine as in Figs. 70 3 and 11. The said film spool 116 is then turned by attaching a special key (not shown) to the spindle 238 (Fig. 18) which passes through the camera mechanism (Fig. 17) engaging the take-up spool 118 through the U shaped slot 267 (Fig. 75

25). The film is then wound in a clockwise direction, the over-running clutch permitting the camera to remain stationary until the openings 164 and 166 in the film strip 112 (Fig. 19) uncover the contacts 128 and 130 (Fig. 10). These contacts complete the circuit as in Fig. 53, whereby there will be current flowing through the contacts 128 and 130 (Fig. 10) through the winding of the electromagnet 414 (Figs. 29, 30, 39, 45) and through the signal lamp 415 (Fig. 3).

Fig. 50 shows the film strip 112, before the holes 164 and 166 have reached the contact members 128 and 130. Fig. 51 shows the film strip 112 when the contact members are reaching through the holes 164 and 166 of the film strip. Fig. 52 shows the film strip after the holes 164 and 166 have passed by the contact members. Since the camera swings with the door, contacts 194, 192, 186 (Fig. 6) will have been lifted from contact rails 176, 174 and 172. The film strip 112 will have no control over the electrical circuit while the door is open. Therefore to position correctly the strip 112 for the commencement of the first exposure, it is necessary to connect an outside source of current and an indicating lamp to contacts 486 and 487 (Fig. 5). This is usually done by connecting a small cell in series with a lamp, and attaching connections to said contacts 486 and 487. The lamp will then be lighted when the contacts are in position over holes 164, 166, as shown in circuit diagram Fig. 51. The film spool is wound just sufficiently so that the film will be positioned as shown in Fig. 52, which cuts off the current from the winding of the electromagnet 414 (Figs. 45 and 46) as well as the signal lamp 415 (Fig. 3). But while current is now cut off from the electromagnet 414, the hook 426, being caught over the pin 420, maintains the latch bar 408 in the position shown in Fig. 45, in which position it remains until tripped by mechanical pressure which will later be applied to the trip end 430, when the camera travel toward the left moves the cam block 431 over the said trip end.

45 The counter board cover 54 may, if desired, be closed at this time. The closing of the cover 54 closes the safety switches 432 (Figs. 37 to 40). The upper door 52 (Fig. 1) may now be closed and bolted by means of the knob 60 and locked with the key 72 (Fig. 1). The key 78 (Figs. 1 and 3) may be turned to the position indicated in Figs. 36 and 37 to interlock the parts 74, 76, 75, 81 and to raise the latch 406. This also closes switch 433 of the motor circuit. The key 368 (Figs. 1, 20, 21, 31 and 34) is now operated by turning it in a clockwise direction against the resistance of the extension spring 374 from a position as indicated in Fig. 40, to a position as indicated in Fig. 42, which is the limiting point of its rotation.

60 When brought to the position indicated in Fig. 42, it will be, for the time being, held by engagement of the catch 376 with the catch 386. In turning the key from the position shown in Fig. 40 to that shown in Fig. 42, the line switch 344 has been operated from open to closed position. The closing of the line switch 344 completes a circuit as shown in Fig. 53, wherein the motor reversing switch 338 is set to rotate the motor in a direction which moves the camera 84 to the left across the face of the counter board. Since no exposure is made while the camera travels towards the left, the lighting switch 340 is now in the off position.

75 The camera will continue to move in this di-

rection until it reaches the extreme left hand position of its travel, at which time it moves the cam lug 431 upon the trip end 430, thereby releasing the hook 426 from the pin 420, whereupon the spring 416 draws the latch bar 408 5 toward the left. The key 78 has already been turned at this time to interlock the parts 74 and 76, 75 and 81, and to raise the catch 406, the part 418 will be drawn toward the left and under the catch 406, as shown in Fig. 46.

10

When the part 408 has once dropped under the catch 406, the key 78 may not be turned to undo the interlock at 74 and 76, 75 and 81, therefore the door 52 and counter board cover 54 may not be opened except by passing current through 15 the winding of the electromagnet 414, thereby to reset the latch bar 408, as in Fig. 46. That no such electrical connection may be made with the mechanism except by making both film strip exposures will appear later.

20

At substantially the same time that the cam lug 431 is pressed upon the trip end 430, the camera engages the lug 362 (Fig. 19), which moves the bar 104, causing the lever 348 (Figs. 20, 31, 34) to operate the switch 338 to reverse 25 the motor and to operate the switch 340 to turn on the bank of lamps 106 and pilot lamp 401 for the film strip exposure. The same movement of the lever 348 causes the screw 398 to depress the part 394 which releases the catches 30 376 and 386 (Figs. 40, 44), and thereby permits the spring 374 to rotate the key 368 slightly counterclockwise, although not far enough to throw the line switch 344 to the off position, the action of the spring 374 being arrested by reason 35 of the latch 378 catching on the latch 388.

At this time lever 348 will be in position as shown in Fig. 31 and index plate 464 will be in the position shown in Fig. 32, cylinder 470 having been rotated around a distance of one 40 tooth. The machine cannot yet be voted because an opening 465 in index plate 464 has not yet been placed directly under the point of dowel 476, Fig. 32.

During the travel of the camera to the left, 45 no part of the film strip 112 was taken by the feed roll 120 from the spool 116, because of the fact that the unidirectional clutch 215 is inoperative to turn the feed roll when the gear 210 rotates in a direction caused by the left hand movement of the camera. But now that camera movement toward the right has begun, the film strip 112 is drawn from the spool 116 and transferred to the spool 118. The bank of lamps 106, being lit at this time, the exposure of the 55 first part 272 of the film strip 112 begins. At this time the electric circuit will be as represented in Fig. 53.

The camera will now travel toward the right to the right hand limit of its movement. The 60 last portion of the movement of the camera to this position automatically moves the control bar 104 to the right by engagement with the mechanism represented by the parts 362, 326 and 350, whereby the lever 348 operates the motor 65 switch 338 to a position for again reversing the direction of rotation of the motor and operates the lighting switch 340 to the off position which extinguishes the bank of lamps 106 and pilot lamp 401.

70

The parts are now in position clearly shown in Fig. 34, wherein stud 400 attached to the boss 402 (which is a part of lever 348), depresses spring member 380 to the position shown in Fig. 34. This same position of the parts is also 75

shown in Fig. 41, wherein the detent 388 has been moved away from the face of ratchet tooth 378, (which is a part of cam disk 366). This allows cam disk 366 to rotate in a clockwise direction through the action of spring 374, thus moving the switch member 392 of switch 344, thereby breaking the motor circuit and stopping the motor. This action is very clearly indicated in Fig. 40.

10 The above action also causes rocker arm 467 (Figs. 31, 34) to be moved as in position Fig. 34 again rotating cylinder 470 the distance of one pin. This places a notch 465 in index plate 464 directly under the reduced portion 476 of dowel 463, allowing dowel 463 to drop into a notch 465 as shown in Fig. 35. As has previously been explained, this will allow the movement of the entrance lever which releases the curtain lever 445 for voting. And so long as these parts are 20 in this position, voting can continue.

This same movement of the lever 348 (Fig. 20) also causes the set screw 400 to depress the part 396, whereby the catch 388 releases the catch 378 and permits the spring 374 to complete the 25 return of the cam 366 and key 368 to its starting position, which also throws the tumbler 392 of the line switch 344 to the off position, in which position the key 368 may be removed from the lock and carried by the proper official during 30 the voting period. The circuit is now as represented in Fig. 55 except that the film strip 112 and the contacts are as in Fig. 53, wherein the bank of lamps 106 and the pilot lamp 401 are extinguished and the contact members 128 and 35 130 are insulated by the film strip 112 by reason of the fact that the middle portion of the film strip 112, which is now over the contact members, is not provided with openings through which the contact members may extend.

40 It will be recalled that the latch bar 408 has previously been released and drawn toward the left by the spring 416 and that the key 78 has already been turned so that the catch 406 will be in the raised position and the part 418 will 45 now be under the catch 406, as in Fig. 46.

The interlock mechanism 74, 75, 76 and 81 may not be undone to permit access to the camera and counterboard except by energization of the electromagnet 414, which may not 50 now be effected except by completing a second exposure of the film strip 112, and thereby bringing the openings 168 and 170 (Fig. 19) over the contact members 128 and 130 (Fig. 9).

After the voting period has been completed, 55 entrance knob 218 is lowered, the proper official again inserts and turns the key 368, whereupon the mechanism causes a second picture taking cycle to take place exactly like the first except that the second sensitized part 274 of the film strip 112 is exposed at this time instead of the first part 272. When the camera reaches the end of the second picture taking cycle, the contacts 128 and 130 will be again uncovered, this time by the openings 168 and 170 in the film strip 60 112. The circuit will now be as represented in Fig. 49, whereby the electromagnet 414 is energized and the latch bar 408 is drawn thereby to the position shown in said Fig. 49. This will allow the interlock bar 404 to be moved in a 65 downward direction by the key 78 which will permit the camera compartment to be opened so that the magazine can be removed. Before the magazine is removed, however, the film is further wound on spool 118 until all of the film including the trailer part 276 has been completely 70

transferred. At this time the openings in the film strip (Fig. 13) will have passed the contacts 128 and 130, thus opening the circuit through the electromagnet 414.

The magazine can now be removed from the 5 voting machine camera whereupon the circuit will again be as represented in Fig. 55.

From the foregoing description of the operation of the mechanism, it will be evident that 10 no tampering with the camera or with the counter board may be done between the time that the camera takes one picture of the counter board and the time when it has completed taking a second picture thereof, this time interval being the time within which the machine is 15 unlocked for voting.

From the foregoing description of my invention and one embodiment of means for practising the same, it is evident that the practice of my invention involves also the practice of that 20 art or method of photography which is claimed in the application of William H. Petit and myself which eventuated in Patent No. 2,034,441.

In said patent there is disclosed an improvement in the art of photography of the power-fed film strip type for the purpose of insuring accurate utilization of the sensitized area of the film strip in the taking of a series of pictures on said film strip, which includes producing a light for the purpose of signalling the presence of 30 the commencement of the sensitized area at the lens of a camera and utilizing the power fed progress of the film strip itself to effect the production of said light, as stated, whereby certainty of such signalling and consequently a perfect record are secured. In accordance with one embodiment of means for carrying out the 35 said art or method as disclosed in said patent, the film is moved for successive exposures past the lens of a camera, and the film itself serves 40 to insulate terminals of an electric circuit having therein a signal, said insulation being interrupted by the structure of the film itself, such interruption being so correlated with respect to an end of said sensitized area that said signal 45 is caused to function at a time to warn the user of the camera of the position of one of said non-sensitized ends with respect to said lens.

In the present application, there is in addition disclosed and broadly claimed mechanism 50 which includes a barrier with respect to the counting means of any registering or like mechanism, as, for example, a voting machine, and means for making an unimpeachable record and preferably a photographic one, of the said counting means prior to any predetermined manipulation of the said counting means, and for making 55 a second and preferably photographic record of the said counting means subsequent to such manipulation of the said counting means, the 60 said means so correlating the said acts of record making and the act of substantially enclosing or erecting a barrier with respect to the said mechanism that access is prevented to the said enclosure between the commencement of making 65 said first record and the completion of said second record.

The mechanism disclosed in the present application constitutes and embodies important improvements over the disclosure in my said co-pending application Ser. No. 65,260. The mounting of the camera upon a door of the voting machine as disclosed in this application for the first time in the art not only simplifies the mechanism but results in an improved operation of 75

parts, all set forth at length in the specification.

Comparing the disclosure in this application with that of my co-pending application Ser. No. 65,260, it is pointed out that with the mechanism of said application Ser. No. 65,260, if a first photograph were made before the voting begins, the mechanism of said application required the making of a second photograph before the back of the voting machine can be opened and the magazine removed. In the event, however, that the election officials were corrupted to the extent that they omitted the formality of making the photograph before the voting began, it is apparent that the object of the invention as disclosed in said application Ser. No. 65,260 would not be accomplished. The improved disclosure in the present application eliminates the possibility of the omission or failure to take the said first photograph. In other words, the improved structure of the present application is such as to compel the election officials to make a photograph before the voting begins. In the present application (as well as in said application Ser. No. 65,260) it is necessary to make a second photograph, namely, upon the completion of the voting before the magazine can be removed.

By the improved mechanism disclosed in this application, it is necessary to close and lock the machine and make a photograph before the voting machine can be voted. A second picture must be made before the voting machine can be opened to get at the camera and after the said second picture is made the camera mechanism automatically locks the voting machine, so that it can be voted again. This invention is essentially broadly claimed.

By the mechanism herein disclosed I practice the broad method which is claimed in the co-pending application of Petit & Hineline, Ser. No. 739,574, filed August 13, 1934, now Patent No. 2,123,151, dated July 5, 1938, where, as a joint inventor, I disclosed and claimed a method of forestalling and preventing fraud by establishing for preservation a permanent, accurate record of the exact number of votes that have been registered for each candidate or question voted on during a predetermined period of use of a voting machine by one election, including a series of steps therein set forth, which include the photographing of the indicators of the voting machine in their relative positions shortly prior to the commencement of the said election and again shortly following the close of such election.

Having thus described one illustrative embodiment of my invention and the best mode known to me for practising the same, it is to be understood that although specific terms are employed, they are used in a generic and descriptive sense and not for purposes of limitation, the scope of the invention being set forth in the following claims.

I claim:

1. Mechanism for producing a record of an object-surface such as a counting mechanism, which includes in combination; an enclosure for said object-surface; a device for producing and retaining two images of said object-surface, one after the other; access-preventing means to prevent access past said enclosure to the object-surface; and cooperating means operatively associated with said device and said access-preventing-means continuing the action of said access-preventing-means while the said device is producing the first of said images and until it has completed producing the second of said images.

2. Mechanism for producing a record of an object-surface, such as a counter, comprising in combination, a cover for said counter, lock means normally operative to lock or unlock said cover, mechanism for producing and retaining two photographic images of said counter, and means operative by said mechanism that functions to produce the first of said images, to render said lock means incapable of unlocking said cover until said mechanism has finished producing the second of said images.

3. Mechanism for producing a photographic record of an object-surface such as a counting mechanism that is operable during a predetermined time interval to have its numerical value altered, comprising in combination an enclosure for said counting mechanism, a camera within said enclosure operable to produce one photographic record at the beginning of said time interval and another at the end of said time interval, lock mechanism normally operative to permit or prevent the opening of said enclosure, and interlocking means associated with the camera and locking mechanism operative to prevent the opening of said enclosure between the time said camera begins to produce the first of said photographic records and the time at which it has produced the second of said photographic records.

4. Mechanism for producing a photographic record of an object-surface such as a counter board comprising in combination, a cover for said counter board, locking means for said cover, a camera within said cover adjacent said counter board, adapted by relative movement between the camera and counter board to traverse said counter board at least twice and make two photographic records thereof during said traverses, means to unlock said locking means to permit said cover to be opened, and means operative by relative movement pertaining to the taking of the first record to render said unlocking means ineffective, and by said relative movement pertaining to the taking of the second record to render said unlocking means effective.

5. Mechanism for producing a photographic record of an object-surface such as a counter board, comprising in combination, a cover for said counter board, locking means for said cover, means to unlock said locking means for said cover, a camera within said cover, adapted by relative movement with respect to said counter board to make a photographic record thereof, a camera lens, a film strip carried by said camera adapted to be moved during exposure across said lens, said strip being long enough for the making of two photographic records, means operative by relative movement pertaining to the taking of the said first record to render said unlocking means ineffective, and means operative by movement of said film strip at the end of the taking of the said second record to render said unlocking means effective.

6. Mechanism for producing a photographic record of an object-surface such as a counter board, comprising in combination, a cover for enclosing said counter board during operation of the machine, locking means for said cover, manually operable means normally operative to unlock said locking means, a camera within said cover adapted by movement across said board to make a photographic record thereof, a camera lens, a film strip having mechanism controlling structural variations and adapted to be moved across said lens during exposure of said strip, said strip

- being of sufficient length for the making of two photographic records, means operative by camera movement pertaining to the taking of said first record to render said unlocking means not operable, and means operable by such structural variations in the film strip positioned to become operative by movement of the said strip at the end of its taking of said second photographic record to render said unlocking means operable.
10. Mechanism for producing a photographic record of an object-surface such as a machine having registering mechanism, comprising in combination a counter board, a cover for enclosing said counter board, locking means for said cover, means normally operable to unlock the locking means for said cover, a camera positioned within said cover and adapted by movement across said counter board to make a photographic record thereof, a camera lens, a film strip carried by said camera having mechanism controlling cut-away places and adapted to be moved across said lens during exposure, said strip being of sufficient length for the taking of two photographic records, means operable by camera movement pertaining to the taking of said first record to prevent said unlocking means being operated, and means made operative by extending through such cut-away places in the film strip to return said unlocking means to an operative condition, said cut-away places being positioned to become effective at the end of the taking of said second photographic record.
8. Mechanism for producing a photographic record of an object-surface such as a machine having a counter board, comprising in combination a locking means to prevent access to said counter board, interlocking means to hold said locking means in the locked position, a camera, a camera lens, a film strip having mechanism controlling structural variations and adapted to be moved across said lens to make two photographic records of said counter board, and means operative by such structural variations in the film strip positioned to become effective by movement of the film strip near the end of film movement to render said interlocking means ineffective.
9. Mechanism for producing a photographic record of an object-surface such as a machine having registering or like mechanism alterable in numerical value, comprising, an enclosure for said registering or like mechanism having locking means, means to unlock said locking means to permit access to said registering or like mechanism, a camera operable by relative movement with respect to said registering or like mechanism to make two photographic records thereof, a camera lens, a film strip having mechanism controlling structural variations and relatively movable with respect to said lens, said strip being of sufficient length for the two said records, means operable by relative movement between the camera and the registering or like mechanism to render said unlocking means ineffective, and means operable by relative movement between the film strip and the lens effective near the end of said movement and operated by such structural variations to render said unlocking means effective.
10. Mechanism for producing a photographic record of an object-surface such as a machine having a counter mechanism alterable to different numerical values, comprising in combination, a locking means to prevent access to said mechanism, an interlocking means to retain said locking means in locked position, a camera operable by relative movement with respect to said counter mechanism to make one photographic record before and one after it is altered, a camera lens, a film strip relatively movable with respect to said lens for exposure, said strip having mechanism controlling variations and being large enough for the taking of said two records, mechanical means operative by relative movement between the camera and counter mechanism pertaining to the film exposure for the first record to make said interlocking means effective, and an electrical means operative by movement of said film at the end of film exposure for the second record to render said interlocking means ineffective.
11. Mechanism for producing a photographic record of an object-surface such as a machine having a counter mechanism, comprising in combination, a locking means to prevent access to said mechanism, interlocking means to retain said locking means in locked position, a camera, a camera lens, a film strip adapted to be moved with respect to said lens to make photographic records of said counter mechanism, said film strip having mechanism controlling structural variations within its length, an electromagnetic means for rendering said interlocking means ineffective, and contact members operable to complete an electric circuit to operate said electromagnetic means positioned relative to said structural variations to be made effective thereby when said film strip has moved so far as to complete said records.
12. Mechanism for producing a photographic record of an object-surface such as counting mechanism, comprising in combination, an enclosure for said mechanism, interlocking means to hold said enclosure in a locked position, a camera for making a photographic reproduction of said counting mechanism, a sealed cartridge associated with said camera, a photographic film within said cartridge, an electromagnet operative to undo said interlocking means to permit said enclosure to be opened, said film within said cartridge being operative by the camera in making said photographic reproduction and having structural variations to operate said electromagnet.
13. Mechanism for producing a photographic record of an object-surface such as registering or like mechanism, comprising in combination, an enclosure for said mechanism, locking means to hold said enclosure in a locked condition, an electromagnet operative to release said locking means, a camera for making a photographic record of said mechanism, a sealed cartridge associated with said camera, a photographic film within said cartridge, switch-controlling structural variations in said film, an electric switch within said cartridge for controlling said electromagnet through said structural variations, said film within said cartridge being operated by said camera in making said photographic record.
14. Mechanism for producing a photographic record of an object-surface such as registering or like mechanism, comprising in combination, enclosing means for said mechanism, locking means for said enclosing means, an electromagnet for releasing said locking means, a switch for controlling said electromagnet, a camera for making a photograph of said registering or like mechanism and means carried by said camera which move in the making of said photograph, to operate said switch.
15. Mechanism for producing a photographic record of an object-surface such as a machine having a counter mechanism, comprising in combination, a locking means to prevent access to said mechanism, an interlocking means to retain said locking means in locked position, a camera operable by relative movement with respect to said counter mechanism to make one photographic record before and one after it is altered, a camera lens, a film strip relatively movable with respect to said lens for exposure, said strip having mechanism controlling variations and being large enough for the taking of said two records, mechanical means operative by relative movement between the camera and counter mechanism pertaining to the film exposure for the first record to make said interlocking means effective, and an electrical means operative by movement of said film at the end of film exposure for the second record to render said interlocking means ineffective.

record of an object-surface such as registering or like mechanism, comprising in combination, enclosing means for said mechanism, locking means for said enclosing means, releasing means 5 for said locking means, means for operating said releasing means, a camera for making a photograph of said mechanism, and means carried by said camera which move in making said photograph for controlling said operating means.

10 16. Mechanism for producing a photographic record of an object-surface such as a bank of counters, comprising in combination, a camera adapted to traverse said counters to make a photographic record thereof, an enclosure for 15 the counters and camera, an interlocking means, and co-operating means operatively associated with said interlocking means and said camera, thereby to compel the making of two photographic records by said camera before the enclosure 20 may be opened.

17. The structure defined in claim 16 and said cooperating means including a film strip provided with mechanism controlling structural variations adapted to control the said enclosure and 25 an electric circuit through which said variation functions in effecting such control.

18. In combination, counting mechanism, actuating means therefor a barrier to prevent access to said actuating means, means for producing and 30 retaining two photographic images of said counting mechanism, and means operatively associated with said barrier and with means for producing and retaining said images, to prevent access past said barrier to said actuating means for operation 35 of the latter until the first of said images has been so produced.

19. In combination, voting mechanism, counting mechanism therefor, a barrier to prevent access to said counting mechanism, means for producing and retaining two photographic images of said counting mechanism, means operatively 40 associated with said barrier and with means for producing and retaining said images, to prevent access past said barrier to said mechanism until 45 after the second of said images has been so produced, and means interlocking the voting mechanism with the photographic image-producing means, so that the voting mechanism may not be operated until after the first of the two photographic images has been produced.

20. In a voting machine, in combination, voting mechanism, registering means therefor, a barrier to prevent access to said mechanism, means for taking two photographs of said registering means, 55 one before and the other after a predetermined use of said voting mechanism, and means operatively associated with said barrier and with means for taking photographs, to prevent use of said voting mechanism until said first photograph has been made.

21. In a voting machine, in combination, voting mechanism, registering means therefor, a barrier to prevent access to said mechanism, locking means for said barrier, means for taking two 65 photographs of said registering means, one before and the other after a predetermined use of said voting mechanism, and means to prevent unlocking said locking means until after said first photograph has been made.

22. In a voting mechanism, in combination, registering means for said voting mechanism, the latter having an entrance knob and a curtain lever, means for taking two photographs of said registering means one before and the other after 70 a predetermined use of said voting mechanism,

and means to lock said entrance knob and said curtain lever against use before the first photograph has been made and also after the commencement of the taking of said second photograph. 5

23. In a voting machine, in combination, voting mechanism, registering mechanism therefor, means for taking two photographs of said registering means one before and the other after a predetermined use of said voting mechanism, 10 and interlocking means to prevent voting (i. e. use of the voting mechanism) before the first photograph has been made.

24. In a voting machine, in combination, registering mechanism therefor, a barrier constituting 15 a part of said voting machine and preventing access to the said registering mechanism, said barrier including a cover that, when closed, is in juxtaposition to the said registering mechanism and prevents access thereto, photographic mechanism so constructed and mounted and arranged upon the inside of said cover that, when said cover is closed, the said photographic mechanism, when operated, takes a photograph showing all of said registering mechanism in the existing relative 20 location of the parts, and cooperating means to cause said photographic mechanism with said door closed and only then to make at least one such photograph of said registering mechanism.

25. In a voting machine, in combination, registering means therefor, a barrier constituting a part of said voting machine and preventing access to the said registering mechanism, said barrier including a cover hinged so as to open outwardly and downwardly, said cover, when closed, having 35 its inner face in juxtaposition to the said registering mechanism, and a camera mounted upon the inner face of said cover for picture-taking traversing movement across the entire registering mechanism only when the said cover is closed. 40

26. In a voting machine, in combination, registering means therefor, a barrier constituting a part of said voting machine and preventing access to the said registering mechanism, said barrier including a cover that, when closed, is in juxtaposition to said registering mechanism and prevents access thereto, photographic means mounted upon the inner surface of said cover for picture-taking traversing movement thereon across the entire registering mechanism only when the 50 cover is closed, traversing mechanism including gearing, part whereof is directly carried by the said body portion of the voting machine, and part whereof is directly carried by the inside of said cover for traversing said photographic means 55 across the entire face of said registering mechanism, and means for operating said photographic means to cause said photographic means to take a picture of the said registering means during 60 such traversing movement.

27. In a voting machine, in combination, voting mechanism, registering means therefor, a barrier to prevent access to said registering means, means mounted upon said barrier for taking two photographs of said registering means one before and the other after a predetermined use of said voting mechanism, the said voting machine having a voting machine release key, and means to prevent turning of said key between the 65 time the camera begins to take the said first photograph and the time at which it has completed the second said photograph.

28. In a voting machine, in combination, voting mechanism, registering means therefor, a 70

75

barrier to prevent access to said registering means, means carried by said barrier for taking first and second photographs of said registering means, and means to render the voting machine 5 unsuitable for the act of voting before a first photograph has been made of said registering means.

29. In a voting machine, in combination, voting mechanism, registering means therefor, a 10 barrier to prevent access to said registering means, means carried by said barrier for taking photographs of said registering means, and means to render the voting machine unsuitable for the act of voting before a photograph has been made 15 of said registering means, and also unvotable after a second photograph has been made of said registering means.

30. In a voting machine, in combination, voting mechanism, registering means therefor, said 20 voting mechanism having locking means, a barrier to prevent access to said registering means, a camera operatively mounted upon said voting machine for taking photographs of said registering means, and means operatively connected to 25 said voting machine and to said camera for necessitating the locking of the voting machine before a picture can be taken by said camera of said registering means.

31. In a voting machine in combination, voting mechanism, registering means therefor, a barrier having locking means to prevent access 30 to said registering means, a camera operatively mounted upon said voting machine for taking photographs of said registering means, and means operatively connected to said voting machine and 35 to said camera for necessitating the locking of the voting machine before a picture can be taken by said camera of said registering means, and cooperating means whereby a second picture 40 must be taken by said camera before the said voting machine can be unlocked.

32. In a voting machine, in combination, voting mechanism, registering means therefor, a barrier having locking means to prevent access 45 to said registering means, a camera operatively mounted upon said voting machine for taking photographs of said registering means, and means operatively connected to said barrier and to said camera for necessitating the locking of the barrier before a picture can be taken by said camera 50 of said registering means, cooperating means whereby a second picture must be taken by said camera before the said barrier can be unlocked, and cooperating means whereby after said second 55 picture has been made the voting mechanism is automatically locked.

33. In a voting machine, voting mechanism, registering means therefor, means to lock said voting machine against voting, a camera operatively connected with said voting machine to photograph said registering means, and means to prevent use of said voting machine until a picture has been made by said camera of the said 60 registering means.

34. In a voting machine, voting mechanism, registering means therefor, means to lock the voting machine against voting, a camera operatively connected with said voting machine and having means for taking two photographs of said 65 registering means, and means to prevent the use of said voting means until a picture has been taken by said camera of said registering means and to prevent the use of said voting machine after the said second picture of the registering 70 means has been made by said camera.

35. Mechanism for producing a photographic record of an object-surface such as a bank of counters, comprising, in combination, a camera, means relatively to traverse said bank of counters with respect to the camera so as to make photographic records of said bank of counters, a barrier preventing access to said counters at a time prior to making a first picture by said relative traverse, and interengaging means for locking said barrier closed and means operatively 10 associated with said camera to release said lock following completion of the second picture by said camera.

36. In a voting machine, in combination, voting mechanism, registering means therefor, a 15 barrier to prevent access to said mechanism, means for taking two photographs of said registering means, one before and the other after a predetermined use of said voting mechanism and means for locking said voting mechanism 20 against use after the second photograph has been made, through the operation of taking the second photograph.

37. Mechanism for producing (when a sensitized surface is carried by the herein referred to 25 camera) a photographic record of an object-surface, such as registering or like mechanism, comprising in combination, enclosing means for said registering or like mechanism, locking means for said enclosing means, releasing means for 30 said locking means, means for operating said releasing means, a camera for making a photograph of said registering or like mechanism, and means carried by said camera, which means moves in the functioning of said camera for controlling said operating means for the releasing means, said means carried by the camera being a flexible sheet or strip having a structural variation or variations for controlling said operating means through the movement of said flexible 35 sheet or strip with respect to the lens of the 40 camera.

38. Mechanism for producing an unimpeachable record of the values expressed by the counting means of registering or like mechanism, including in combination, enclosing means for said mechanism, a camera for making photographic records of said registering or like mechanism, locking means for said enclosing means, releasing means for said locking means, and cooperating 45 means operatively associated with said releasing means and said camera, thereby to compel the making of a photographic record of said counting means prior to any specified manipulation of said counting means, and also the making of a second photographic record of said counting 50 means subsequent to such manipulation of said counting means prior to the releasing of the locking means for the enclosing means, whereby access is prevented to the enclosure between the 55 commencement of making the first photographic record and the application of said second photographic record.

39. Mechanism for producing an unimpeachable record of the values expressed by the counting means of registering or like mechanism, including in combination, enclosing means for said mechanism, a camera for making photographic records of said registering or like mechanism, locking means for said enclosing means, releasing means for said locking means, and cooperating 65 means operatively associated with said releasing means and said camera, thereby to compel the locking of said enclosing means as a condition precedent to the making of the said 70

first photographic record, and the making of the said second photographic record a condition precedent to the functioning of said releasing means in its releasing action upon said locking means.

5 40. Mechanism for producing an unimpeachable record of the values expressed by the counting means of registering or like mechanism, including in combination, enclosing means for said mechanism, a camera for making photographic records of said registering or like mechanism, locking means for said enclosing means, releasing means for said locking means, and cooperating means operatively associated with said 10 releasing means and said camera, thereby to compel the locking of the said enclosing means as a condition precedent to the making of a photographic record of the said counting means prior to any specified manipulation of said counting 15 means.

20 41. In a voting mechanism, in combination, registering means for said voting mechanism, entrance-controlling means determining access to or use of the said voting mechanism, means 25 for taking two photographs of said registering means, one before and the other after a predetermined use of said voting mechanism, and means to govern said entrance-controlling means against access to or use of the voting mechanism 30 before the said first photograph has been made and also after the commencement of the taking of said second photograph.

25 42. In a voting machine, in combination, voting mechanism, registering means therefor, means for taking two photographs of said registering means, one before and the other after a predetermined use of said voting mechanism, and means including a lock connected in operation 35 with the photograph taking means, to prevent voting (i. e. use of the voting mechanism) before the first photograph has been made.

30 43. In a voting machine, in combination, registering means therefor, a barrier constituting a part of said voting machine and preventing access to the said registering mechanism, said barrier including a cover that, when closed, is in juxtaposition to said registering mechanism and prevents access thereto, photographic means 40 mounted upon the inner surface of said cover for

picture-taking traversing movement thereon across the entire registering mechanism only when the cover is closed, and yieldingly mounted traversing gearing for said photographic means, so positioned and arranged at least in part upon 5 the voting machine body as to permit members of said gearing in the closing of said cover to yield with respect to each other, to permit closing of said cover without injury to said parts.

44. As a new, assembled or completed, unitary 10 article of manufacture and sale, a door or cover having formations adapting it to be secured as a door or cover to the body or casing of counting mechanism, such, for example, as a voting machine having registering mechanism, said door or 15 cover having a track or guideway secured to the inner face thereof, photographic means mounted upon the said track or guideway for traversing movement therealong in the taking of a picture of such registering mechanism, and gearing 20 means carried by said photographic means, adapted, when said door or cover is secured in intended position to the body or casing and is closed, to interengage operatively with cooperating driving means carried by said body or casing, 25 whereby said door or cover and the said parts thereon may be completed and operatively assembled as a unitary article of manufacture and sale, and then may be readily applied to the said body or casing by means of its said formations. 30

45. In a voting machine, in combination, registering means therefor, a barrier constituting a part of said voting machine and preventing access to the said registering mechanism, said barrier including a cover movably connected to the 35 main portion of the barrier so that when the cover is closed, it is in juxtaposition to the said registering mechanism and prevents access thereto and when moved to open position permits such access, and a camera mounted upon the inner 40 face of said cover whereby, when the cover is closed and the camera is operated, said camera takes a photograph showing said registering mechanism in the existing relative relation of the parts, and cooperative means to cause said camera, consequent upon door closure, to make at least one photograph of said registering mechanism. 45

EDSON S. HINELINE.
